UNITED STATES PATENT OFFICE.

BENJAMIN JOHN LATSHAW, OF BURKBURNETT, TEXAS.

OIL-BURNER.

1,217,019.

Specification of Letters Patent.

Patented Feb. 20, 1917.

Application filed April 28, 1916. Serial No. 94,192.

To all whom it may concern:

Be it known that I, BENJAMIN J. LATSHAW, a citizen of the United States, and a resident of Burkburnett, in the county of Wichita and State of Texas, have invented certain new and useful Improvements in Oil-Burners, of which the following is a specification.

My invention is an improvement in oil burners, and the invention has for its object to provide a simple, inexpensive, but efficient burner of the character specified, wherein mechanism is provided for spraying a mixture of steam and oil into the furnace, in such manner that the oil and steam will be thoroughly mixed and atomized before it is delivered to the furnace.

In the drawing:

Figure 1 is a side view of the improved burner with parts in section,

Fig. 2 is a vertical sectional view through the burner and the spraying device,

Fig. 3 is a section on the line 3—3 of Fig. 2, looking in the direction of the arrows adjacent to the line,

Fig. 4 is a perspective view of the spray head.

The present embodiment of the invention is shown in connection with a wall of the furnace 1, the said wall having an internally threaded opening 2, which is engaged by the threaded end of a pipe 3. A locking nut 4 is threaded onto the pipe at the opening, and a mixing mechanism is connected 35 with the outer end of the pipe 3.

The said mechanism comprises a T 5, the T having one end connected with the pipe 3, and a steam pipe 6 is connected with the other end of the T. An oil feed pipe 7 is 40 connected with the lateral branch of the T, and it will be noticed that the steam pipe is of smaller diameter than either the pipe 3 or 7.

The pipe 6 has an enlarged head 8 which 45 engages the end opening of the T, and the end of the pipe 6 and the head are internally threaded to receive one end of a pipe 9. This pipe 9 is threaded for a considerable distance into the pipe 6, and it is of a length 50 sufficient to extend entirely through the T and slightly beyond the opposite end thereof, that is the end adjacent to the pipe 3.

The pipe 9 is enough smaller than the interior of the pipe 3, to provide an annular 55 passage between the said pipes, and it will be evident that when the steam is injected

through the pipe 9, a current will be created and the oil fed through the pipe 7 will be carried with the steam into the furnace. The pipe 3 is in practice, about eighteen 60 inches in length, so that the steam and the fuel must travel this distance in intimate contact.

A spray head of particular form is provided at the outlet end of the pipe 3. This 65 head may be formed from Babbitt metal or the like and is in the form of a split ring 10 having thickened or enlarged portions 11, at opposite sides of the ring. The inner faces of these thickened portions 11 70 are plane, as shown, so that the opening through the spray head is approximately square, and the spray head is so arranged that the thickened portions 11 are at the top and the bottom of the pipe 3. The ring 75 is also cut away between the enlargements as shown in Fig. 4, at each end, so that the ends of the thickened portions extend beyond the ends of the ring proper.

In operation, the oil is fed in any suitable 80 or desired manner through the pipe 7, and when the steam is turned on through the pipe 6, the mixed oil and steam will be fed through the spray head into the furnace. Because of the fact that the mixed oil and 85 steam must travel for a comparatively long distance in intimate contact, the oil will be thoroughly cut up and atomized, and in addition it will be heated to the same temperature as the steam and will be delivered 90 to the furnace in the form of a highly heated spray, in the best possible condition for quick combustion. Practically all of the oil is gasified before it is delivered into the furnace. It will be evident that the thickening 95 of the ring 10, reduces the bore of the said ring, and the ring as a whole, reduces the bore of the mixing pipe 3.

I claim:

1. An oil burner comprising a mixing 100 and delivery pipe adapted to open at one end into the furnace and having at the other end a T, a fluid fuel supply pipe connected with the lateral branch of the T, a steam pipe connected with the other end of the T 105 in alignment with the mixing pipe, and having a delivery nozzle detachably connected therewith and extending through the T and into the mixing pipe, said mixing pipe being of comparatively great length, to provide 110 for a comparatively long travel of the steam and oil in intimate contact, and a

spray head in the delivery end of the mixing pipe, said spray head being a split ring having oppositely arranged thickened portions making the bore of the head approximately square in cross section.

2. An oil burner comprising a mixing and delivery pipe adapted to open at one end into a furnace, and having connected with the other end a steam supply pipe, and having a lateral branch forming a fluid

fuel supply pipe, the steam pipe having a delivery nozzle extending beyond the lateral branch, said mixing pipe being of comparatively great length to provide for a relatively long travel of the steam and fuel in intimate contact, and a spray head in the delivery end of the mixing pipe and comprising a split ring having oppositely thickened portions. 15

BEN. JOHN LATSHAW.
